UNITED STATES PATENT OFFICE.

WILLIAM PATTERSON, OF SALEM, NEW JERSEY.

ROAD-SCRAPER.

SPECIFICATION forming part of Letters Patent No. 253,310, dated February 7, 1882.

Application filed May 4, 1881. (No model.)

To all whom it may concern:

Be it known that I, WILLIAM PATTERSON, a citizen of the United States, residing at Salem, in the county of Salem, State of New Jersey, have invented a new and useful Improvement in Road-Scrapers, which improvement is fully set forth in the following specification and accompanying drawings, in which—

Figure 1 is a top or plan view of the scraper embodying my invention. Fig. 2 is a vertical section thereof. Fig. 3 is a rear view of the scraper plate or blade.

Similar letters of reference indicate corresponding parts in the several figures.

15 My invention relates to improvements in the class of road-scrapers more especially shown in Letters Patent Nos. 47,977 and 178,948, granted to me respectively May 30, 1865, and June 20, 1876; and said invention consists of 20 the combination, with a latching-lever and a scraper-plate, of an adjustable tongue, with which said lever engages.

It also consists of the scraper-plate and the tongue, in combination with a latching-lever having a depending rearwardly-extending toe, and a notch in front of said toe, as will be hereinafter set forth.

Referring to the drawings, A represents the scraper board or plate, which is pivoted to the 30 upright arms of the circular frame B, which arms serve as supports for said scraper-plate, the frame having fitted to it the sliding connection C of the draft pole or shafts D, and pilot or caster wheel E, for adjusting the position of the wheel relatively to the desired obliquity of draft of the scraper.

To the frame B, at one end thereof, is fitted the adjustable latching-lever F, by which the scraper-plate is held in operative position, and 40 which, when raised and detached from said plate, permits the latter to be tilted when required, this being conveniently accomplished by the hand-lever G connected to the plate A.

Rising from the scraper-plate at the portion 45 immediately beneath the lever F is a tongue, H, which, adapted to engage with the notch a of said lever F, is formed with a vertical slot, b, through which passes a bolt, c, for connect-

ing the tongue to the plate, and admitting of the vertical adjustment of the tongue relatively to the angle at which the plate is set and the time when the tongue is to engage with the notch a of the lever F, and thus lock the plate and lever.

Depending from the lever F, just in the rear of the notch a, is a rearwardly-curved toe or guard, J, which is sufficiently long to extend below the top edge of the plate or of the tongue H, whereby, in returning the scraper-plate from its tilted position, which is generally accomplished with some force, it raises the lever F and strikes the toe J, so that the rearward motion of the plate is limited, and the notch a of the lever unfailingly engages with the tongue H, thus securely holding the scraper-plate in 65 upright position. The scraper-plate is of twisted or mold-board form, so that when earth, &c., is scraped by the plate it is carried thereby in a constant stream to one side of the road, and prevented from overturning until it is about 70 to leave the plate—say at the overhanging part d—which also prevents the earth, &c., passing rearward over the top of the plate.

The bottom edge or part, A', of the scraper-plate is removable from the main portion A'' thereof, and formed with a shoulder, e, against which the portion A'' is fitted, said part A' being screwed or bolted to the main portion A'', and thus securely held. When the part A' is worn or fractured it may be removed and 80 repaired or replaced, as required.

Having thus described my invention, what I claim as new, and desire to secure by Letters Patent, is—

1. The scraper-plate, in combination with the 85 adjustable tongue and the latching-lever, substantially as and for the purpose set forth.

2. The scraper-plate A, having a tongue, H, in combination with a latching-lever having a depending rearwardly-extending toe and a 90 notch in front of said toe, operating substantially as and for the purpose set forth.

WILLIAM PATTERSON.
